UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

BOBBIN RELEASE FOR LOOM WEFT-REPLENISHING MECHANISM.

Application filed June 13, 1925. Serial No. 36,980.

This invention relates to loom weft replenishing mechanism of the multi-color type and it is the principal object of the invention to provide means for releasing a bobbin 5 which has moved to transfer position but has not been transferred because of improper boxing of the shuttle.

In multi-color weft replenishing mechanisms the bobbins of differing colors are 10 arranged in parallel vertical stacks and at indication of weft exhaustion a bobbin of the proper color is released to move toward transfer position. When the indicating shuttle returns to the magazine side of the 15 loom the transfer will take place provided the shuttle is properly boxed, but if the shuttle should fail to be in position to receive the bobbin, the replenishing mechanism is reset but the bobbin which was to 20 have been transferred is still in transferring position and must be removed. Heretofore devices have been provided for releasing an untransferred bobbin but they have been made to operate either by regularly actuated 25 mechanism subject to undue wear or they have been operated only when needed but on the forward stroke of the lay. In the latter construction the bobbins are occasionally caught between the lay and some stationary part of the loom with resultant 30 breakage and in the former devices the wear of the parts is excessive. It is a further object of my invention to provide a bobbin release operative only at the time of a revoked 35 transfer to release an untransferred bobbin on the backward stroke of the lay.

With these and other objects in view which will appear as the description proceeds my invention resides in the combination and 40 arrangement of parts hereinafter described and set forth in the claims.

In the accompanying drawings wherein I have shown one embodiment of my invention,

45 Fig. 1 is a vertical central section through the lower portion of a multi-color weft replenishing mechanism looking toward the loom and showing the bobbin support in normal open position,

50 Fig. 2 is a horizontal section on line 2—2 of Fig. 1.

Fig. 3 is a fragmentary view showing certain parts of the invention in the position they assume when a transfer is about to take place,

55 Fig. 4 is a view similar to Fig. 1 but showing the parts in the position they assume after a transfer has been revoked and before resetting of the bobbin support to normal open position,

60 Fig. 5 is a detail view showing the retaining lever, and

65 Fig. 6 is a detail of the unlocking lever which controls the lever shown in Fig. 5.

In the drawings wherein I have shown the invention as applied to a four color weft replenishing mechanism, the magazine frame 10 has bobbin compartments 11 which discharge the bobbins by mechanism not shown to a common transfer position defined by a 70 fixed support 12 and a movable support 13. The support 13 is pivotally connected as at 14 to the bottom of the link 15 the upper end of which is pivoted on one of the tie rods 16 of the replenishing mechanism. The 75 support 13 has a rearwardly and upwardly extending arm 17 through which extends a pin 18 movable in a slot 19 formed in link 20 and engaging screw 21 secured in said link. The link 20 is movable about a fixed 80 pivot 22 and the screw 21 is adjustable to vary the position of the support 13. A tension spring 23 is interposed between the arm 17 and an offset in the upper end of link 15 and serves to hold the pin 18 against the 85 screw 21. A coil spring 24 surrounding tie rod 16 is secured to the link 15 and tends normally to move the lower end thereof toward the left as shown in Fig. 1. A shuttle 90 feeler 25 is adjustably secured in a carrier 26 which is secured to a stud 27 rotatable in a bearing 28. The carrier 26 has an arm 29 which is pivotally connected to a rod 30 the upper end of which is controlled by mechanism not shown herein but set forth in 95 Patent No. 1,030,748. At the time of transfer the rod 30 is depressed to lower the shuttle feeler 25 so that it may be raised by the shuttle if the latter is not properly boxed.

100 Stop screw 31 is secured by link 15 to engage the frame 10 and limit movement of said link and support 13 under action of coil

spring 24. The matter thus far described is of common construction and for a more complete description of the same reference may be had to the aforesaid patent and also to Patent No. 1,366,950.

My improvements relate to means for controlling the movement of the bobbin support 13. In carrying out my invention, I secure an unlocking lever 40 to the stud 27 (Fig. 2) so that the lever 40 and the shuttle feeler 25 will move together. A retaining lever 41 (Fig. 5) is pivoted loosely on a fixed stud 42 (Fig. 2) and has a forwardly projecting arm 43 from which projects an offset lug 44. The link 15 is provided with a cam face 45 which terminates in a recess 46 formed on said link 15. The lever 41 (Fig. 5) has a depending arm 47 on which is mounted a spring plunger 48 held normally in raised position by a spring 49.

The plunger 48 has a loose sliding fit in its lower bearing 47^a on the arm 47 and the upper end of the plunger is guided for swinging transverse movement in its slotted upper bearing 47^b. A flange 48^a yieldingly engages the under side of the bearing 47^b and normally holds the plunger in the position shown in Fig. 1.

The lever 40 which moves with the shuttle feeler has a releasing point 50 which is normally in contact with the under side of the arm 43 as shown in Fig. 1. Said lever 40 is also provided with a depressing finger 51 which is normally in advance of the upwardly projecting end of the plunger 48. The lay 52 carries a box back 53 from the rear side of which extends a trip 54 positioned for engagement with the plunger 48 when the latter is depressed with the bobbin support 13 in bobbin retaining position.

In operation, the parts are normally in the position shown in Fig. 1, the lever 41 being positioned with its lug 44 in the recess 46 of the link 15, holding the support 13 in open position. The plunger 48 is normally in rearward raised position and clears the trip 54 as the latter moves back and forth with the lay. At the time of transfer, the rod 30 is depressed to give the stud 27 a counterclockwise oscillation, as shown in Fig. 1, the effect of which is to move the unlocking lever 40 and cause the point 50 thereof to raise the arm 43. This action results in moving the lug 44 out of the recess 46, permitting the coil spring 24 to move the lower end of the link 15 to the left, carrying the support 13 to closed or bobbin retaining position. The position of the parts at this stage of the operation is as shown in Fig. 3, the plunger 48 being located in its forward position and above and out of the path of the trip 54.

As the plunger 48 thus moves forward, it may be engaged by the finger 51, but clears the finger by swinging yieldingly rearward

in its slotted upper bearing 47^b, such swinging movement depressing the point of the plunger and causing it to slip under the finger 51 to the position shown in Fig. 3.

As the lay advances, the shuttle feeler 25 will be raised either by engagement with a misplaced shuttle or with the box back 53, which action will move the depressing finger 51 downwardly to lower the plunger 48 to the position shown in Fig. 4. As the lay 75 thereafter moves backwardly, the trip 54 will engage the plunger 48 and rock the lever 41 back to the position shown in Fig. 1, returning the lug 44 to the recess 46 and moving the bobbin support 13 to open or bobbin releasing position.

As the lever 41 is being returned to normal or rearward position, the plunger 48 will be moved from under the finger 51 and the spring 49 will move the plunger upward 85 to normal position, where it will be out of the path of the trip 54.

It is to be understood that the trip 54 and plunger 48 can be made to contact with each other at any desired point in the backward movement of the lay, so that the release of the bobbin 10 can be effected at any desired point. I find that the bobbin can advantageously be released when the lay is about half way back.

From the foregoing, it will be seen that I have provided a bobbin releasing device in connection with a normally open or inoperative support, which operates only at the time of transfer and which releases a bobbin on the backward stroke of the lay at any desired point.

Having thus described my invention, it will be apparent that changes and modifications may be made therein by those skilled in the art without departing from the spirit and scope of the invention and I do not wish to be limited to the details herein disclosed but what I claim is:

1. In a weft replenishing mechanism for looms, a lay, a bobbin support normally in open position to permit a bobbin to pass thereby, means under control of the replenishing mechanism to move said support to closed or bobbin retaining position, and means operatively connected to the support and located behind the lay when the latter is in its extreme forward position, said means being engaged by the lay during the backward stroke of the lay to move said support to open or bobbin releasing position.

2. In a weft replenishing mechanism, a lay, a bobbin support normally in bobbin releasing position, a retaining lever for said support to hold the same in bobbin releasing position, means controlled by the weft replenishing mechanism to move the retaining lever to releasing position, means to move said support to bobbin retaining position,

and means to reset the retaining lever and support to bobbin releasing position during the backward stroke of the lay.

3. In a weft replenishing mechanism for looms, a lay, a bobbin support normally in bobbin releasing position and tending to move toward bobbin retaining position when released, a retaining lever holding said support in bobbin releasing position, means under control of the replenishing mechanism to move said retaining lever to a position to release said bobbin support, and means to return the retaining lever and support to normal bobbin releasing position during the backward stroke of the lay.

4. In a weft replenishing mechanism for looms, a lay, a bobbin support normally in bobbin releasing position and tending when released to move toward bobbin holding position, a retaining lever to hold the support in bobbin releasing position, means under control of the replenishing mechanism to move the retaining lever to release the bobbin support, and connections between the lay and the retaining lever established during backward movement of the lay to move said retaining lever and bobbin support to bobbin releasing position.

5. In a weft replenishing mechanism, a lay, a bobbin support normally in bobbin releasing position and tending normally to move to bobbin holding position when released, a retaining lever to hold said support in bobbin releasing position, means to move the retaining lever to a position to release the support, a plunger carried by said retaining lever, connections between said means to release the retaining lever and the plunger to depress the latter, and a trip carried by said lay to engage the plunger during the backward movement of the lay to move said retaining lever and support to bobbin releasing position.

6. A mechanism as set forth in claim 5, in which the plunger has a movement to free itself from the retaining lever as the lever moves with the shuttle feeler to the operative position of the feeler, and in which the plunger is engaged and depressed by the retaining lever as said lever moves with the shuttle feeler to the inoperative position of said feeler.

In testimony whereof I have hereunto affixed my signature.

ALBERT A. GORDON.
